DRYING DEVICE.

Application filed September 7, 1927. Serial No. 217,956.

This invention relates to drying devices and more particularly to devices for drying clothes and the like.

An important object of the invention is 5 to provide a novel device for drying clothes and particularly women's silk dresses which usually must be dried relatively rapidly and out of direct sunlight to prevent the colors of the goods from fading or running.

A further object is to provide novel air directing means for projecting air into the interior of the garment for drying it.

A further object is to provide a drying 15 device adapted particularly for use in connection with an ordinary cooling fan for projecting currents of air into a garment to dry it.

A further object is to provide a novel 20 air tunnel having an outlet end over which may be arranged a garment to be dried, the tunnel further being provided with an inlet end adjacent which the impeller of an ordinary cooling fan may be arranged.

25 A further object is to provide a substantially arcuate sheet metal casing in the form of an air tunnel having a horizontally arranged inlet opening adjacent which a fan may be arranged and a substantially vertical enlarged outlet opening over which the garment to be dried may be supported.

A further object is to provide novel means 30 for supporting the garment above the air tunnel.

35 A further object is to provide novel means for holding the lower edges of the garment with respect to the air tunnel so that air currents may be directed into the garment.

Other objects and advantages of the 40 invention will become apparent during the course of the following description.

In the drawings we have shown one embodiment of the invention. In this showing,

45 Figure 1 is a front elevation,

Figure 2 is a section on line 2—2 of Figure 1, parts being shown in elevation, and,

Figure 3 is a fragmentary side elevation of a portion of the garment holding device, parts being shown in section.

Referring to the drawings the numeral 50 10 designates a base adjacent one end of which is arranged a preferably tubular standard 11 having a support 12 slidable therein and adapted to be secured in posi-

tion by a thumb screw 13. The upper end of the support is extended inwardly substantially horizontally as at 14 and terminates in a hook 15 upon which may be supported a garment hanger 16 of the usual type. 60

An air tunnel indicated as a whole by the numeral 17 is arranged over the base 10 and is substantially arcuate in shape. The tunnel is provided with inlet and outlet ends 18 and 19 arranged horizontally and vertically respectively. The tunnel is formed of sheet metal and is preferably made up of a plurality of sections 20 secured together at their edges, as will be apparent. The lower portion of the tunnel may be supported 70 upon the base by a block 21 or any other suitable means. A bracket 22 is secured to the tunnel adjacent its upper end and is provided with an aperture through which the standard 11 extends whereby the upper 75 end of the tunnel is supported by the standard.

The impeller 23 of an ordinary cooling fan is arranged in the inlet end of the tunnel and is surrounded by the usual guard 80 24 which preferably fits within the tunnel. The impeller is driven by the usual motor 25 arranged on a base 26 supported on the base 10.

85 A plurality of cross arms 27 are arranged over the outlet end of the tunnel and are secured together at their centers by rivets 28 or other fastening means. Each of the arms is provided adjacent opposite ends with vertical portions 29 engaging the wall of the tunnel and secured thereto by rivets or the like 30. Each end of each of the arms 27 overhangs and extends outwardly of the wall of the tunnel, as indicated at 31, and a preferably tapered socket 32 is soldered or otherwise secured to each overhanging end to frictionally receive one end of a clothes clip 33 of the usual type. Similar sockets may be arranged on each end of each of the arms inwardly of the walls of the tunnel to receive clothes clips to be secured to the ends of garments which are smaller than the tunnel, as will be apparent. As shown in Figure 1, a garment 35 may be arranged on the hanger 16, and the lower end of the garment may be engaged by the outer clothes clips 33. 100 105

The operation of the device is as follows:

After a garment has been washed it may 110 be arranged on a hanger 16, and the latter

may be supported by the hook 15. One arm of each of the clips 33 is frictionally held in position in each of the sockets 32, and the free arm of each clip may be depressed to permit the clip to receive a portion of the lower end of the garment. If the diameter of the lower end of the garment is not sufficiently large to permit the edge portion to be engaged by the outer clips 33, it will be apparent that the inner clips may be employed. These inner clips also may be used when drying dresses provided with underskirts. The motor 25 is then operated to drive the impeller 23 to propel a current of air through the tunnel, this current of air being discharged upwardly into the garment to effect the drying thereof. Obviously some of the air will pass through the material of the garment to facilitate the drying action. The inlet end of the tunnel is approximately the same size as the fan 23 and since the tunnel is closed throughout its length, the entire current of air will be utilized for the drying operation.

It is to be understood that the form of the invention herewith shown and described is to be taken as a preferred example of the same and that various changes in the shape, size and arrangement of parts may be resorted to without departing from the spirit of the invention or the scope of the subjoined claims.

We claim:

1. A garment drying device comprising a tunnel having inlet and outlet ends, means arranged adjacent the inlet end of said tunnel for impelling currents of air therethrough, a support adapted to hold a garment adjacent the outlet end of the tunnel, a

plurality of cross arms supported on the outlet end of the tunnel, sockets carried by said arms, and a plurality of garment clips having portions adapted to be received in said sockets and adapted to subtend a portion of the garment over said outlet end. 40 45

2. A garment drying device comprising a tapered arcuate tunnel having its smaller and larger ends arranged horizontally and vertically respectively, a base for supporting said tunnel, a fan arranged adjacent the smaller end of said tunnel to impel air therethrough, a support carried by said base and having a portion overhanging and arranged above the larger end of said tunnel to support a garment thereover, and means carried by said tunnel adjacent its larger end for subtending a portion of said garment thereover. 50 55

3. A garment drying device comprising a tapered arcuate tunnel having its smaller and larger ends arranged horizontally and vertically respectively, a base for supporting said tunnel, a fan arranged adjacent the smaller end of said tunnel to impel air therethrough, a standard carried by said base, a support vertically slidably in said standard and having a portion overhanging and arranged above the larger end of said tunnel to support a garment thereover, and a plurality of clips arranged around the outlet 60 65 70 end of said tunnel on cross arms carried by said tunnel for subtending a portion of the garment thereover. 70

In testimony whereof we affix our signatures.

LOISE B. McCRAY.
WILLIAM V. MORGAN.
